UNITED STATES PATENT OFFICE.

ROBERT L. FRINK, OF BELLE VERNON, PENNSYLVANIA, ASSIGNOR TO WINDOW GLASS MACHINE COMPANY, OF PITTSBURG, PENNSYLVANIA, A CORPORATION OF NEW JERSEY.

OIL AND GAS BURNER.

982,584.

Specification of Letters Patent. Patented Jan. 24, 1911.

Application filed March 8, 1906. Serial No. 304,884.

To all whom it may concern:

Be it known that I, ROBERT L. FRINK, of Belle Vernon, Fayette county, Pennsylvania, have invented a new and useful Oil and Gas 5 Burner, of which the following is a full, clear, and exact description, reference being had to the accompanying drawings, forming part of this specification, in which—

Figure 1 is a sectional elevation of a 10 burner embodying my invention; Fig. 2 is an end view of the regulating valve dial; Figs. 3 and 4 are sections on the line III—III and IV—IV respectively of Fig. 1; Fig. 5 is a detail view of the nozzle, 15 partly in section and partly in side elevation; Fig. 6 is an end view of the nozzle; and Fig. 7 is a detail sectional view of a modification.

My invention is designed to provide a simple and efficient burner adapted for use with either oil or gas as a fuel; and it consists in the novel construction, arrangement and combination of parts all substantially as hereinafter described and pointed out in the 25 appended claim.

In the drawings, the numeral 2 designates a hollow shell or casing having a transverse interior partition 3 located near one end, and an internal spider 4 near the opposite end, 30 said partition and spider dividing the interior of the shell into a steam chamber 5, an air or gas chamber 6, and a mixing and combustion chamber 7, the latter having a contracted discharge or nozzle portion 8.

9 designates an oil supply pipe which extends centrally within the body portion 2, through a stuffing box 10 and through the partition 3 and spider 4, being inclosed between said partition and spider by surrounding tube 11 which is secured at its rear end to the partition 3 and whose forward end extends beyond the spider 4 and terminates in a nozzle portion 12. The tube 11 opens at its rear end into the steam chamber 5, 45 and is of sufficient diameter to leave a surrounding space around the oil supply tube 9 through which steam may flow. The forward end of the pipe or tube 9 is provided with a nozzle 13 having a flared discharge 50 13^a, and a series of exterior spaced lugs or

projections 14 which serve to center the nozzle within the tube 11 and provide spaces for the escape of the steam into the mixing and combustion space 7. The inner walls of these spaces may be parallel with the axis 55 of the burner, as shown in Fig. 5 or they may be parallel with the inner wall 12^a of the contracted nozzle portion 12, as shown in Fig. 7 so that they will tend to centrally deflect or divert the jets of steam which pass there-through, and thereby alter the proportion of oil drawn through the nozzle 13.

The oil is supplied to the pipe 9 by the pipe 15, and the feed is regulated by means of a needle valve 16. The stem of this valve 65 is provided with a pointer 18 which, in connection with a fixed dial plate 17, indicates the position of the valve and forms means for determining the proper feed.

Steam is admitted to the chamber 5 70 through the inlet ports 19. In the drawing I have shown two of these ports located opposite to each other, but may use one only.

20 designates an air or gas inlet extension of the body portion 2, which opens into the 75 chamber 6. The air thus supplied passes through the openings of the spider 4 into the combustion space 7 where it comes in contact with the oil and steam as the latter are brought together. The air inlet extension 20 is provided with a lateral opening, normally closed by a screw plug 21, as indicated in dotted lines in Fig. 1, and which provides means for the connection thereto of a gas pipe, should it be desired to use gas as 80 a fuel. The area of the inlet passage is great enough to admit a sufficient volume of gas 85 for this purpose.

The advantages of my invention consist in the simplicity of the construction, and in 90 the efficiency of the burner for use with either oil or gas as a fuel, so that by changing the angle of the steam orifices either a reducing or oxidizing flame may be produced, by changing the injector effect on the 95 oil in pipe 9.

What I claim is:—

In a burner, the combination of a casing having a transverse partition and a transverse spider support dividing the casing into 100

several chambers, a steam inlet behind the partition and a steam nozzle connected thereto and supported in the spider and having a converging mouth, an oil supply tube centered and supported in the steam pipe and provided with a regulating valve outside the casing, said oil pipe having a head with converging grooves coöperating with the

converging mouth of the steam pipe, substantially as described.

In testimony whereof, I have hereunto set my hand.

ROBERT L. FRINK.
